Primary Examiner—Jeffrey Asch**[57] CLAIM**

The ornamental design for a device for supporting compact disc cases and other objects, as shown and described.

DESCRIPTION

FIG. 1 is a perspective view of a device for supporting compact disc cases and other objects showing my new design;

FIG. 2 is a front view thereof; and,

FIG. 3 is a sectional view thereof, along the section line 3—3 in FIG. 2.

The rear view is substantially the same as the front view; and, the left and right sides of the device are substantially identical. The broken lines in the drawings represent compact disc cases which can be supported on the device and are for illustrative purposes only and form no part of the claimed design.
